UNITED STATES PATENT OFFICE.

CHESTER H. BEACH, OF RACINE, WISCONSIN, ASSIGNOR TO WISCONSIN ELECTRIC COMPANY, A CORPORATION OF WISCONSIN.

VALVE GRINDER.

Application filed November 6, 1920. Serial No. 422,323.

To all whom it may concern:

Be it known that I, CHESTER H. BEACH, a citizen of the United States, residing at Racine, in the county of Racine and State of Wisconsin, have invented certain new and useful Improvements in Valve Grinders, of which the following is a specification.

My invention relates to improvements in valve grinding attachments.

10 One object of the invention is to provide a valve grinding attachment which may be quickly and conveniently applied to an electric motor to adapt the latter for grinding valve seats, and which may be removed 15 with equal facility to permit said motor to be used for other purposes. Another object is to provide an electric valve grinder of this character which requires only one hand to hold it in place, when in use.

20 In the accompanying drawings I have illustrated two embodiments of the invention.

Fig. 1 is a side elevation of a small portable electric motor with the valve grinding attachment connected therewith.

25 Fig. 2 is a front elevation of the attachment, on a slightly larger scale.

Fig. 3 is a bottom view thereof.

Fig. 4 is a side elevation of a modified form of attachment.

30 Fig. 5 is a plan view thereof, and Fig. 6 is an end elevation.

The electric motor 10 may be of any type adapted for the purpose, and is preferably a small universal motor provided at one end 35 with a handle 11, and at the other end with a reduction gearing incased in a housing 12 and carrying a chuck 13 adapted to receive small drills or other tools. The motor casing is also provided with a pair of projections or bosses 14 which serve to position 40 the grinding attachment, as hereinafter described.

The grinder attachment comprises a suitable frame 15, having a pair of enlarged extremities 16 provided with recesses which fit over the bosses 14. Said frame has a head 17 with an opening therethrough providing a bearing for the reduced end 18 of the shaft 19. The grinding blade 20 is set 50 into and secured in the end of said shaft and is nearly in alignment with the armature shaft. Said shaft has an arm 21 secured thereto, at the shouldered end thereof, which is pivotally connected with a link 22,

the latter being connected also to a shorter 55 arm 23, which is fixed to a short shaft or pin 24 passing also through an opening in the head 17. Said shaft 24 is received within the chuck 13 and gripped thereby in the usual manner. With this arrangement it 60 will be seen that as the shaft 24 rotates, the shaft 19 will be given an oscillating movement.

An anti-friction washer 25 is located between the arm 21 and the head 17 and takes the thrust arising during the grinding operation. This thrust is communicated by the frame 15 to the projection 26 on the motor casing, the latter being nearly in line with the point of the grinding blade 20. 70 (See Fig. 1.) This arrangement prevents binding or cramping, such as would occur if the thrust were taken by the chuck, particularly as the thrust would be eccentric with reference to said chuck. The bosses 14 75 by their engagement with the frame 15 also hold the attachment against rotation, when the motor is running. The device as a whole may, therefore, be operated with one hand only as distinguished from certain prior 80 electrically driven grinders in which one hand is required to hold the motor, the other hand holding the grinder proper against rotation.

The pin 24 is long enough to be slipped 85 into the opening in the chuck before the projections 14 enter the recesses in the extremities 16, thereby facilitating the attachment of the device to the motor. It will be seen that the grinding attachment is simply 90 slipped in place and requires no fastening means whatever, other than the tightening of the chuck about the pin 24, which would be necessary in any case.

In the form of invention shown in Figs. 4, 95 5 and 6, the axis of rotation of the grinder shaft is at an angle with the axis of rotation of the armature shaft instead of being substantially in line therewith as in the first 100 form of device described. With the arrangement shown in the drawings the angle is preferably a right angle, but may be any angle. The chuck rotates the pin 24, the latter turning a cam 27 mounted in a bracket 28; said bracket supporting also the reduced 105 end 29 of the grinder shaft 30, the axis of said shaft being arranged at an angle with the axis of the shaft 24. The reduced end

29 carries the arm 31 having a pin 32 which fits within a groove on the cam 27 and is therefore oscillated as said cam rotates.

5 The invention is not limited to the preferred embodiments described herein, as various other forms may be devised which fall within the scope of the appended claims.

I claim as my invention:

1. The combination with an electric motor 10 comprising a complete unitary structure, of a chuck secured to the motor shaft, a valve grinding attachment comprising a rotatable part and a stationary part, said rotatable part being removably secured to said chuck 15 and said stationary part having means co-operating with said motor to prevent rotation thereof.

2. The combination with a portable motor having a handle and a chuck, of a valve 20 grinding attachment operatively attached to said motor by means of said chuck, and means interposed between said motor and said attachment to prevent rotation of the latter whereby said handle serves as a 25 single handle for the combined motor and grinder.

3. In apparatus of the class described, a 30 shaft, a rotatable pin offset from the axis of said shaft, a driving connection interposed between said pin and shaft, means for driving said pin, and a supporting member offset with respect to said pin and extending upwardly in alinement with said shaft.

35 4. The combination with an electric motor having a chuck, of a valve grinding attachment therefor comprising a support, an oscillating spindle, means on one of said parts for positioning said support so as to aline said spindle with the motor shaft and offset means connected with said chuck for driving said spindle from said motor shaft.

5. The combination with a motor, having 45 a chuck offset from the axis of the armature shaft, of a grinder frame carrying a rotatable spindle, a co-operating projection and recesses for positioning said frame on the motor to aline said shaft with the armature shaft, said pin being engaged by said 50 chuck, and links for driving said shaft from said pin.

6. The combination with a portable motor and a grinding attachment, of a pin on said attachment engaged by the driving

member of the motor and telescoping means 65 on said grinder and motor for positioning the two relatively and co-operating upon movement in a direction to engage said pin and driving member.

7. The combination of a portable motor, 60 a grinding attachment therefor, a rotatable pin on one part and means on the other part for gripping said pin to transmit rotary motion and to lock the parts together, the parts also having positive engaging elements for preventing relative rotation.

8. The combination with a portable motor having a casing, a handle, a reduction gearing and driving shaft eccentric with respect to the armature shaft, of a grinding attachment comprising a body and a spindle rotatably carried thereby in substantial alinement with said armature shaft, said body engaging said casing to transmit the thrust of the spindle thereto and said spindle having eccentric driving connections engaging the driving shaft on the motor and driven thereby without transmitting an eccentric thrust thereto.

9. The combination with an electric motor having a chuck, of a spindle supported by said chuck at one side of the longitudinal axis of the latter, means for driving said spindle from said chuck, and a support interposed between the upper end of said spindle and said motor.

10. The combination with an electric motor having a chuck, of a spindle supported by said chuck at one side of the longitudinal axis of the latter, means for driving said spindle from said chuck, and a support interposed between the upper end of said spindle and said motor, said spindle being in alinement with the armature shaft of the motor.

11. In combination, a portable motor, a chuck carried by said motor and offset with respect to the armature shaft thereof, a grinding attachment held by said chuck and having a spindle depending therefrom in alinement with said armature shaft, and means interposed between said attachment and said motor for preventing rotation of the former.

In testimony whereof, I have subscribed 105 my name.

CHESTER H. BEACH.
